(57) **CLAIM**

The ornamental design for a toothbrush handle, as shown and described.

DESCRIPTION

FIG. 1 is a perspective view of a toothbrush handle embodying our new design;

FIG. 2 is a top plan view thereof;

FIG. 3 is a left side elevational view thereof;

FIG. 4 is a bottom plan view thereof;

FIG. 5 is a front end view thereof; and,

FIG. 6 is a rear end view thereof taken from the free end of the handle of said toothbrush handle.

The broken line showing of bristle head and bristles is for illustrative purposes only and forms no part of the claimed invention.
